UNITED STATES PATENT OFFICE

ALEX M. SPRADLIN, OF CLIFF, KENTUCKY

DESIGN FOR AN INKWELL STAND

Application filed March 30, 1928. Serial No. 26,074. Term of patent 3½ years.

To all whom it may concern:

Be it known that I, ALEX M. SPRADLIN, a citizen of the United States, residing at Cliff, in the county of Floyd and State of Kentucky, have invented a new, original, and ornamental Design for an Inkwell Stand, of which the following is a specification, reference being had to the accompanying drawing, forming part thereof.

I claim:—

The ornamental design for an ink well stand, as shown.

ALEX M. SPRADLIN.
